PRODUCTION OF ARTICLES OF COMMERCE

Jacquelin E. Harvey, Jr., Washington, D. C.

Application February 26, 1942, Serial No. 432,496

5 Claims. (Cl. 196—53)

The instant process relates to production of valuable liquids from tars and fractional parts thereof, crude and/or refined.

This application is a continuation-in-part of my application Serial No. 345,438 filed July 13, 1940, now Patent No. 2,291,323, dated July 28, 1942, for "Synthesis of valuable liquids," copending herewith, as to all matter common to the two applications.

An object of the present invention is the subjection of tars and fractions thereof, crude and/or refined, to the action of hydrogen and an inert gas, in step-wise manner, whereby to provide valuable liquids, as for instance materials useful as solvents, plasticizers and/or wood preservatives.

A further object of the instant process is the production of materials, the characteristics of which are dependent upon, among other things, process variables in the final operating step.

Other objects of the instant process will be apparent from the following disclosure.

Suitable starting materials of the process of the present invention include tars and fractions thereof derived from the high temperature of carbonization of coal, as for instance high temperature coke oven tar and gas house tar.

Especially suitable as starting material is the refined pitch secured from high temperature coke oven tar or gas house tar. A refined pitch may conveniently be secured by stripping high temperature coal tar to produce a residuum of pitch, semi-coke or coke, and fractionating the overhead material to recover a liquid useful as a wood preservative and a higher boiling fraction boiling predominantly above 355° C., said fraction last named being the refined pitch in question.

Among other things, the instant process may be viewed broadly as providing a process for the production of materials useful as solvents, plasticizers and/or wood preservatives by subjecting at least a portion of the starting material, in step-wise manner, to the controlled action of hydrogen and an inert gas.

The following examples will serve to illustrate the general principles upon which the practice of the present invention is based, as well as the process of the present invention.

Example 1.—A crude high temperature coal tar boiling substantially 3% at 210° C. is passed through a high pressure reaction chamber at 425° C. and 225 atmospheres pressure whilst contacting a flow of hydrogen or hydrogen containing gas in the order of 18,000 cubic feet per barrel material treated. The time of contact is about

four hours and the catalyst is selected from the group consisting of oxides and sulfides of tungsten including tungstates. The thus beneficiated material will be found to have lowered boiling points, specific gravity and viscosity. It will be found that newly induced materials boiling below 200° C. have been formed. An inspection, periodic if necessary, of the beneficiated material will disclose that fractional increment, depolymerization and/or hydrogen absorption were linear functions of the time element. The beneficiated material is stripped to 315° C. to provide the vaporous low boiling stripped fractions as the intermediate starting material of the instant process. The vaporous stripped low boilers are heated to 400° C. and thereafter are commingled with an inert gas which had previously been heated to 700° C. The proportion of heated inert gas is so selected as to provide in the commingled material an equalization temperature of about 530° C. The time of contact of the commingled materials is so selected as to provide dehydrogenating conditions on the stripped low boiling materials above mentioned. However, instead of super-heating the vaporous intermediate starting material, the evolved vapors may be directly contacted with the preheated inert gas.

With some intermediate starting materials produced in accordance with the instant process, periods of a fractional part of a minute will be found to provide the desired dehydrogenating conditions; however, longer periods may be used, as for instance one or more minutes. In the instance of using the longer periods of time, with or without a more elevated temperature, plasticizing properties of usable quality will be found to have been induced.

The point at which the hydrogen beneficiated material is stripped is determined by the need at hand.

The accompanying drawing represents a self-explanatory flow sheet of the process.

After the desired period of contact of the commingled materials has been effected at the named or desired temperature, the materials are passed to suitable condensing and if desired fractionating apparatus to provide a condensed material which is the finally dehydrogenated material of the present process. The condensed overall dehydrogenated material, or fractional parts thereof, will be found to have solvency, plasticity and/or toxicity in excess of its intermediate starting material.

A convenient test for solvency may be had by evaluation of the well known Kauri-butanol

number or aniline points. A convenient test for plasticity is disclosed at page 96, et seq. "The Technology of Solvents," Dr. Otto Jordon, Chemical Publishing Co. of New York, Inc. Toxicity may be evaluated in accordance with "Method of conducting the tests," page 2, Tech. Bull. No. 346, U. S. Dept. Agr., 1933.

In the first step of the process wherein the tar is subjected to the action of hydrogen at super-atmospheric pressure, the stripped material flowing from the beneficiation and which provides the intermediate starting material of the instant process may conveniently be secured by distillation, release of gas pressure and/or stripping action of gas. After the stripping action, the stripped low boiling materials may be condensed or fractionally condensed and only a part thereof subjected to the subsequent action of the inert gas; or, the stripped low boiling materials without condensation may be subjected to the dehydrogenating action of the inert gas.

If desired water in vaporous form may be supplied in conjunction with the inert gas. As inert gases employable in the instant process may be mentioned carbon monoxide, carbon dioxide, hydrocarbon gases inert under process conditions, nitrogen or the like. Any of the gases named in combination with vaporous water may also be employed.

The initial heat of the inert gases named and/or steam may be secured from any convenient source, as for instance by passing through heated tubes, or the inert gases may consist of inert combustion gases, such as flue gases heated to the desired temperature.

Because of the wide variation in possible intermediate starting materials, as aforementioned, no arbitrary statement is possible concerning the necessary percentage of inert gases and/or steam, nor is it necessary. A few trials with any of the intermediate starting materials will definitely show the percentage necessary. Using some intermediate starting materials, 75% inert gas and/or steam will prove satisfactory for certain dehydrogenating conditions. However, as will now become obvious, the percentage of inert gas will be dependent on, among other things its character and temperature, time of contact and so forth.

One of the preferred starting materials of the instant process is a refined pitch described in the foregoing. The refined pitch in question has a critical and unexpected treatment period in the hydrogen treating step. This critical period of treatment is in the order of about three hours, and which if exceeded produces adverse and undesirable reactions, as for instance loss of newly induced fractions, polymerization and/or lowered hydrogen absorption.

When subjecting the crude high temperature coal tar of Example 1 or stripped high temperature coal tar to the action of hydrogen for the production of newly induced fractions and/or depolymerization of the molecular complexes it has been found that the percentage of said newly induced fractions and/or depolymerization are linear functions of the time element for periods of two to eight hours or longer. When subjecting crude high temperature coal tar to the action of hydrogen for two, five and eight hour periods it has been found that fractional increment, reduction in insolubles and/or depolymerization are linear functions of the time element. The period of treatment in the first step (of hydrogen action) is so selected as to provide fractional

increment, depolymerization and/or hydrogen absorption as a linear function of the time element dependent upon the material.

Thus the period chosen for a crude coke oven tar characterized by all the inherent filth, insolubles and coke residue common to such a product may be as long as eight hours or longer. It has been found that even for periods up to twenty hours when treating certain of the crude tars mentioned, fractional increment, depolymerization and/or hydrogen absorption were linear functions of the time element.

Thus the state of the art is that when subjecting crude high temperature tar, characterized by all the filth, insolubles and coke residue common to such material, to the action of hydrogen for production of newly induced products, fractional increment, depolymerization and/or reduction of insolubles is a linear function of the time element within the periods disclosed.

It is an accepted principle in the art that a distillate of a crude hydrocarbon is more amenable to the action of hydrogen than its crude parent material and consequently should have a longer permissible period of treatment by or with hydrogen wherein fractional increment, depolymerization and/or hydrogen absorption are linear functions of the time element. Applicant has discovered a distillate of high temperature coal tar or the like that does not conform to the accepted teaching above named in that there exists a relatively short and critical period of treatment by or with hydrogen and which if exceeded causes reverse and undesired reactions, that is to say, causes loss of fractional increment, polymerization and/or lowered hydrogen absorption if the relatively short and unexpected critical time period is exceeded. The distillate in question is the refined pitch of the instant process and has a critical time of treatment by or with hydrogen in the order of about three hours.

This critical period of hydrogen treatment for applicant's refined pitch was totally unexpected in that this material is a distillate and consequently had been relieved of a major portion of the inherent filth, insolubles, and/or coke residue of the parent stock.

Example 2.—In accordance with the instant process a refined pitch boiling substantially 20% at 355° C. is charged to a high pressure vessel and hydrogen pumped in to an upper limit of 1800 pounds per square inch. Thereafter the material is treated for two hours and forty-five minutes at a temperature of 425° C., the meanwhile maintaining the contents of the vessel in an agitated condition. At the end of the named period the vessel and its contents are cooled. The beneficiated refined pitch is then distilled to an upper limit of 325° C. The evolved vapors are then contacted with one part of methane and two parts of steam and passed through heating coils wherein a temperature of 465° C. is attained for the commingled materials. Thereafter the commingled materials are contacted with an inert carbon-containing or hydrocarbon gas or gases previously heated to about 710° C. The quantity or percentage of the added heated inert gas or gases last named is so selected as to provide an equalization temperature of about 510° C. The time of contact of the finally commingled materials heated to the named temperature is maintained for a period sufficient to dehydrogenate, at least to a degree, the vaporous

intermediate starting material. The treated material is condensed and will be found to have solvency, plasticity and/or toxicity in excess of the intermediate parent material. If desired, superatmospheric pressure may be maintained in that part of the process characterized by contacting the stripped low boilers from the hydrogen beneficiating step with the preheated inert gas. Superatmospheric pressure may be maintained in any part of the flow of the process. As an example, the inert preheated gas or gases may be supplied under pressure.

The condensed material may be fractionated to provide substances useful as solvents, plasticizers and/or wood preservatives. When using certain intermediate starting materials and when the temperature in the final process step is held around or above 500° C., certain fractions of the condensed material will be especially suitable as plasticizers, binders or the like, and more especially this condition obtains if the intermediate starting material represents a deep cut on the first beneficiated material.

The overall finally beneficiated material may be fractionated to provide solvents and plasticizers of any boiling range, as for instance substitutes for the conventionally manufactured materials as noted in the following tabular data:

	°C.
Benzol	78-120
Toluol	100-150
Hi-Flash naphtha	150-200
Heavy naphtha	150-290
Plasticizers	160-360

In the event a solvent or the like is recovered to an upper limit of 270° C., the residual portion may serve as a wood preserving impregnant by virtue of its increased toxic value, as it will be found that the process controls of the final step of the process induces, among other things, toxicity.

Thus it will be seen that the instant process provides for (1) depolymerizing high temperature coal tar fractions in the presence of hydrogen whilst controlling the period of treatment to provide fractional increment, depolymerization and/or hydrogen absorption as the linear function of the time element, (2) stripping low boiling materials from the beneficiated tar, and (3) thereafter contacting at least a portion of the stripped low boiling materials with that percentage of previously heated inert gas or gases adapted to provide an equalization temperature and other conditions conducive to and effecting dehydrogenation, at least to a degree, of the intermediate starting material.

In the first step of the instant process characterized by the action of hydrogen, pressures from slightly above atmospheric may be employed, as for instance when employing a tungsten oxide or sulfide or catalysts similarly effective. However, higher pressures may be employed, as for example 20, 50, 100 or 200 atmospheres or higher when using less effective catalysts.

In the step characterized by the action of hydrogen temperatures of between 300° C. and 550° C. serve to illustrate the present process; however, temperatures under pressure conditions that cause no inordinate coking are preferred, as for example 375-435° C. or somewhat higher.

Example 3.—An especially attractive form of practicing the instant process resides in contacting a mixture of crude high temperature coal tar

fractions, as for example a mixture boiling 200-345° C., with a flow of hydrogen at a pressure of 1-50 atmospheres and at a temperature chosen between the limits of 300-550° C., as for instance between 400-500° C., say 425° C. The catalyst is selected from a group consisting of oxides and sulfides of tungsten including tungstates. The time of contact is four hours and hydrogen flow about 16,000 cubic feet per barrel feed stock. The beneficiated material characterized by lowered specific gravity, coke residue and viscosity is stripped to an upper limit of say 290° C. and subjected to the second step of the process, as for example as set forth in Examples 1 and/or 2.

Example 4.—A refined pitch is subjected to the action of a flow of hydrogen for a period of about two hours and forty-five minutes. The catalyst is selected from a group consisting of oxides and sulfides of tungsten including tungstates. The temperature is selected between the range of 375-550° C., as for instance between 400-500° C., say 435° C. The total pressure in the operation is maintained at about 100 atmospheres or lower as for instance at about 20 atmospheres or lower. At the end of the named period the material under treatment is stripped by gas movement to an upper limit of about 325° C., or the stripping may be performed at a higher or lower point. Thereafter the stripped low boiling material is treated in the presence of a preheated inert gas in a manner similar to operations disclosed in Examples 1 and/or 2.

In the first process step characterized by the action of hydrogen, reaction conditions may be secured by intermittent operation, as for instance in a bomb or the like. Continuous practice may also be employed by passing the starting material through a reaction chamber in the presence of a flow of hydrogen or hydrogen-containing gas. The flow of hydrogen is maintained so as to preclude substantial carbonaceous deposition or polymerization. Gas flows of in the order of 15,000-20,000 cubic feet per barrel material treated will prove satisfactory under certain conditions. However, higher or lower gas flows may be employed. All catalysts effective in the presence of hydrogen may be employed separately or in admixture or in conjunction with the catalysts aforementioned. However, the hydrogen step may be practiced without catalysts. When employing very efficacious catalysts, pressures only slightly above atmospheric may be employed. As a specific example of the more effective hydrogenation catalysts may be mentioned the oxides and/or sulfides of metals including halogens or derivatives thereof. These catalysts or others in any form or shape may be employed, as for instance extended on carriers, pelleted, comminuted, extruded or in any form or shape promoting surface contact.

In the final step of the process characterized by contacting the intermediate starting material with preheated inert gas, the final equalization temperature is selected between the limits of 300-750° C., as for example between 425° and 700° C., say 510° C., 525° C. or 535° C.

Minor changes may be made without departing from the spirit of the present invention.

I claim:

1. In the production of valuable liquids from the refined pitch produced by stripping high temperature coal tar to a point to produce a residual selected from the group consisting of pitch, semi-coke and coke, and fractionating the overhead material to recover a liquid useful as a

wood preservative, and a higher boiling fraction boiling predominantly above 355° C., the process which comprises: subjecting said higher boiling fraction to the action of hydrogen for a period not in excess of about three hours, whereby to avoid loss of newly induced low boiling fractions; stripping newly induced low boiling fractions from the hydrogen treated material; and increasing the boiling points of at least a chosen portion of said stripped fractions by subjecting same to the dehydrogenating action of a preheated inert gas in the absence of an added catalyst at a temperature selected between the limits of about 300°-750° C.

2. In the production of valuable liquids from the refined pitch produced by stripping high temperature coal tar to a point to produce a residual selected from the group consisting of pitch, semi-coke and coke, and fractionating the overhead material to recover a liquid useful as a wood preservative, and a higher boiling fraction boiling predominantly above 335° C., the process which comprises: subjecting said higher boiling fraction to the action of hydrogen for a period not in excess of about three hours, whereby to avoid loss of newly induced low boiling fractions; stripping newly induced low boiling fractions from the hydrogen treated material; increasing the boiling points of at least a chosen portion of said stripped fractions by subjecting same to the dehydrogenating action of a preheated inert gas in the absence of an added catalyst at a temperature selected between the limits of about 300°-750° C.; and fractionating the last named beneficiated material to segregate a solvent.

3. In the production of valuable liquids from the refined pitch produced by stripping high temperature coal tar to a point to produce a residual selected from the group consisting of pitch, semi-coke and coke, and fractionating the overhead material to recover a liquid useful as a wood pre-

servative, and a higher boiling fraction boiling predominantly above 355° C., the process which comprises: subjecting said higher boiling fraction to the action of hydrogen for a period not in excess of about three hours, whereby to avoid loss of newly induced low boiling fractions; stripping newly induced low boiling fractions from the hydrogen treated material; increasing the boiling points of at least a chosen portion of said stripped fractions by subjecting same to the dehydrogenating action of a preheated inert gas in the absence of an added catalyst at a temperature selected between the limits of about 300°-750° C.; and fractionating the last named beneficiated material to provide a solvent boiling preponderantly between 100° C. and 150° C.

4. In the production of valuable liquids from the refined pitch produced by stripping high temperature coal tar to a point to produce a residual selected from the group consisting of pitch, semi-coke and coke, and fractionating the overhead material to recover a liquid useful as a wood preservative, and a higher boiling fraction boiling predominantly above 355° C., the process which comprises: subjecting said higher boiling fraction to the action of hydrogen at a pressure not in excess of about 100 atmospheres and a temperature in excess of 300° C. for a period not in excess of about three hours, whereby to avoid loss of newly induced low boiling fractions; stripping newly induced low boiling fractions from the hydrogen treated material; and increasing the boiling points of at least a chosen portion of said stripped fractions by subjecting same to the dehydrogenating action of a preheated inert gas in the absence of an added catalyst at a temperature selected between the limits of about 300°-750° C.

5. The process of claim 4 wherein the last named beneficiated material is fractionated to recover a solvent.

JACQUELIN E. HARVEY, JR.
